NIGHTGOWN

Marjorie Heaton Brandes, Chicago, Ill.

Application November 17, 1937, Serial No. 174,926

5 Claims. (Cl. 2—73)

My invention relates to nightgowns and is more specially concerned with a nightgown with a built-in brassière. Among the objects of my invention is an improved manner of incorporating the brassière in the nightgown whereby it is not only concealed, but its presence does not become apparent and yet the brassière is afforded adequate support.

Another object is a functionally improved, but ornamental, shoulder strap serving both the nightgown and the built-in brassière.

The foregoing together with further objects, features and advantages of my invention are set forth in the following description of a specific embodiment thereof illustrated in the accompanying drawing, wherein:

Fig. 1 is a rear view of a nightgown embodying my invention with the left half of the rear of the bodice portion broken away to show the inside or rear elevation of one-half of the brassière;

Fig. 2 is a front elevation of the upper part of the nightgown;

Fig. 3 is a section taken on the line 3—3 of Fig. 1 showing the right armhole portion looking from within;

Fig. 4 is a section taken on the line 4—4 of Fig. 1;

Fig. 5 is a planar development of the inside face of the brassière; and

Fig. 6 is a detail section taken on the line 6—6 of Fig. 3 showing the piping at the margin of the armhole.

The nightgown indicated generally as 10 comprises a skirt portion 11, and a bodice portion 12. The front of the bodice portion may be formed by a left front piece 12L and a right front piece 12R joined to the respective edges of the back portion of the bodice by side seams 13 and to the upper edge of the skirt portion 11 by oblique front seams 14 which meet at the center adjacent the upper edge of the bodice, where they may be dressed by an ornamental ribbon bow 15. A sash-like tie or belt 16 may extend from the side seams 13 in line with the seam of the back of the bodice to the back of the skirt portion and continue as loose ends which may be tied.

The built-in brassière 17 is preferably formed from a left half 17L and a right half 17R, as shown in Fig. 5. The bottom edge of the brassière is preferably in the outline of a broad V and sewn by bottom seams 18 to the front portion of the bodice. I prefer that the bottom seams 18 of the brassière and the seam 14 which joins the front of the bodice portion to the front

of the skirt be coincident and, in fact, a common seam. The center portion 19 of the bottom seam of the brassière, however, is preferably independent of the seams 14 and serve merely to join the two halves of the brassière. The respective ends 5 of the brassière are sewn into the side seams 13 or otherwise attached to the bodice portion.

A reinforcement 20 extends more or less vertically across the medial portion of each half 17L and 17R of the brassière. This reinforcement 10 20 may be tape sewn across the brassière; or each half of the brassière may in turn be formed of two portions joined along the line of the reinforcement 20 with such overlapping of the fabric as to constitute a satisfactory tape-like 15 reinforcement. Each reinforcement 20 extends into a brassière shoulder strap 21, which may either be an integral extension of the reinforcement 20 or an additional piece anchored to the reinforcement 20 at its upper end. Preferably 20 the strap 21 is of tubular construction which may be formed by sewing together the edges of a bias tape.

At each side of the front portion of the bodice 12, the upper edge thereof and the end edge or 25 armhole opening margin converge to form a point 12P. A front supporting strap 22 for the bodice extends upwardly from the point 12P. This may conveniently be a continuation of the piping 22' which extends along the margin of 30 the armhole opening. Somewhat similarly a rear supporting strap 23 for the bodice, which may conveniently be a continuation of the piping 23', extends upwardly from the rear shoulder portion 35 of the bodice.

The strap 23 extends over the shoulder and down to the point 12P where it is anchored, as shown best in Fig. 3. On the other hand, the straps 21 and 22 extend up over the shoulder and down to the rear shoulder portion of the 40 bodice where they are anchored. Thus the three straps 21, 22 and 23 extend in more or less parallel and close relation between the front and rear shoulder portions. As an expedient for holding them in association as a unit and to augment the ornamental effect, I prefer to braid 45 the three straps 21, 22 and 23 as shown in the drawing.

For the sake of greater clarity the terminal portions of the straps are shown in an unnatural 50 and distended arrangement in Fig. 3. It will be understood that in practice they look like a unitary braided strap, as indicated in the upper portion of Fig. 3.

The interbraiding of the three straps has the 55

further functional advantage of a cable in which any undue strain on one strap is, to a large extent, borne by all three, and there is thus much less danger of breaking any individual strap.

5 The interbraiding of the three straps also tends to hold the strap 21 and hence the brassière in proper vertical relation to the point 12P and in turn the bodice, without the necessity of a fixed anchorage of the strap 21 at the point 12P or at any other point on the front of the bodice. Such an anchorage would be relatively inflexible and might tear lose, whereas the interbraiding of the strap 21 with the other straps forms a more yielding anchorage, and hence one which is less likely to tear.

10 13 As shown best in Fig. 4, the distance starting at the seam 18 and running along the reinforcement 20 and the strap 21 up to the braided portion is less than the distance at the same region along the body of the bodice itself. Thus, while the brassière is supported in such a manner as to be fairly tight, the portion of the bodice which covers it is left with sufficient fullness to drape itself over the brassière in a natural manner calculated to conceal the presence of the brassière. The attachments of the brassière to the inside of the nightgown follow the natural construction lines of the nightgown and hence do not reveal or suggest the presence of the brassière therebeneath. The brassière is, nevertheless, adequately supported.

15 18 The term "brassière" as herein used connotes a brassière of the type where the material of the brassière covers or overlies the breast, as distinguished from a mere support or uplift.

20 23 While I have described and illustrated this specific embodiment of my invention, I contemplate that many changes and substitutions may be made thereover without departing from the scope or spirit of my invention.

25 I claim:

1. A nightgown comprising a skirt, a bodice front, a bodice back, a brassière, common side seams joining together the ends of the brassière, bodice front and bodice back, common front seams converging upwardly joining together the lower edges of the bodice front, the lower edges of the brassière and the upper front edge of the skirt, and shoulder strap means connecting the upper edges of the bodice front and back and supporting the upper edges of the brassière, the upper portion of the bodice front extending above and covering, but outwardly free from, the brassière and of greater vertical fullness than the brassière, and tape-like reinforcing means extending more or less vertically across the face of each side of the brassière and supportingly connected with the shoulder strap means.

2. A nightgown comprising a skirt, a bodice front, a bodice back, a brassière, common side seams joining together the ends of the brassière, bodice front and bodice back, common front seams converging upwardly joining together the lower edges of the bodice front, the lower edges of the brassière and the upper front edge of the skirt, and shoulder strap means connecting the upper edges of the bodice front and back and sup-

porting the upper edges of the brassière, the upper portion of the bodice front extending above and covering, but outwardly free from, the brassière and of greater vertical fullness than the brassière, the shoulder strap means at each shoulder comprising three interbraided straps, the first extending from the brassière to the bodice back, the second from the bodice front to the bodice back and the third from the bodice back to the bodice front.

3. A nightgown comprising a skirt, a bodice front, a bodice back, a brassière, common side seams joining together the ends of the brassière, bodice front and bodice back, common front seams converging upwardly joining together the lower edges of the bodice front, the lower edges of the brassière and the upper front edge of the skirt, and shoulder strap means connecting the upper edges of the bodice front and back and supporting the upper edges of the brassière, the upper portion of the bodice front extending above and covering, but outwardly free from, the brassière and of greater vertical fullness than the brassière, the shoulder strap means at each shoulder comprising three interbraided straps, the first extending from the brassière to the bodice back, the second from the bodice front to the bodice back and the third from the bodice back to the bodice front, the straps being otherwise unanchored.

4. A nightgown comprising a skirt, a bodice front, a bodice back, a brassière, common side seams joining together the ends of the brassière, bodice front and bodice back, common front seams converging upwardly joining together the lower edges of the bodice front, the lower edges of the brassière and the upper front edge of the skirt, and shoulder strap means connecting the upper edges of the bodice front and back and supporting the upper edges of the brassière, the upper portion of the bodice front extending above and covering, but outwardly free from, the brassière and of greater vertical fullness than the brassière, and tape-like reinforcing means extending more or less vertically across the face of each side of the brassière and supportingly connected with the shoulder strap means.

5. A nightgown comprising an upper front body portion, and a brassière mounted inwardly thereof and covered thereby, lines of stitching extending along the lower edge of the brassière securing it to the body portion, and along the ends of the brassière securing them to the body portion at its sides, tape-like reinforcing means extending across substantially vertical medial lines of the right and left halves of the brassière, and shoulder strap means connected to the reinforcing means for supporting the brassière with greater tautness than the overlying region of the body portion, whereby the latter loosely drapes itself over, and belies the presence of, the brassière.

MARJORIE HEATON BRANDES.
